MINIATURE RECIRCULATING PUMP FOR DISPLAYS AND THE LIKE

Damon B. Johnson and Charles B. Faison, Oklahoma
City, Okla., assignors to Little Giant Corporation,
Oklahoma City, Okla., a corporation of Oklahoma

Filed June 30, 1960, Ser. No. 61,176

Term of patent 14 years

(Cl. D65—1)

FIGURE 1 is an elevational view of a miniature recirculating pump for displays and the like, showing our new design;

FIGURE 2 is another elevational view thereof taken from the left side of FIGURE 1;

FIGURE 3 is another elevational view thereof taken from the back of FIGURE 1;

FIGURE 4 is a top plan view thereof; and
FIGURE 5 is a bottom plan view thereof.

We claim:

The ornamental design for a miniature recirculating pump for displays and the like, as shown.
